UNITED STATES PATENT OFFICE.

WEBSTER C. ESTES, OF BROOKLYN, NEW YORK.

DESIGN FOR A WOODEN BOX.

SPECIFICATION forming part of Design No. 24,991, dated December 17, 1895.

Application filed November 18, 1895. Serial No. 569,376. Term of patent 14 years.

To all whom it may concern:

Be it known that I, WEBSTER C. ESTES, a citizen of the United States, residing at Brooklyn, in the county of Kings and State of New York, have invented and produced a new and original Design for a Wooden Box, of which the following is a specification, reference being had to the accompanying drawings, in which—

Figure 1 is an elevation; Fig. 2, a plan, and Fig. 3 a vertical section.

The general configuration of the box is round, and the leading features of my design consist in the curved sides contracted toward the center of the box and the flat top and bottom surfaces.

The design of the cover A consists in the flat top *a* and the downward-curving converging sides *b b*.

The design of the body B consists in the flat bottom *c*, the upward-curving converging sides *b' b'* and the circular rib *d* adjacent to the upper end.

In the design of the box as a whole the curved sides *b' b'* are contracted toward the center of the box and the flat top and bottom surfaces are parallel.

What I claim is—

The design for a wooden box, substantially as shown and described.

Signed by me this 16th day of November, 30
A. D. 1895.

WEBSTER C. ESTES.
